UNITED STATES PATENT OFFICE.

HAAKON HELLAN, OF BELLEVUE, PENNSYLVANIA.

REVERSING VALVE FOR FURNACES.

Application filed July 11, 1922. Serial No. 574,189.

To all whom it may concern:

Be it known that I, HAAKON HELLAN, a citizen of the United States, residing at Bellevue, in the county of Allegheny and 5 State of Pennsylvania, have invented new and useful Improvements in Reversing Valves for Furnaces, of which the following is a specification.

My invention relates to reversing valves 10 for furnaces; and the principal object thereof is to provide for the gas valve a gas-tight seal by means of tar condensed from the gas as it traverses the valve chambers. Another object is to provide novel gas and 15 air valves, which may in one form thereof close their gas and air inlets before the exhaust outlets are opened, and may close the latter before the former are opened to prevent the gas and air from shortcircuiting to 20 the stack. Another object is to provide novel means for operating the valves and limiting their throws so that they can not engage their seats when closing. Other objects appear hereinafter.

25 Referring to the accompanying drawings, Fig. 1 is a central vertical section of a gas-controlling valve constructed in accordance with my invention; Fig. 2, a similar section of an air-controlling valve embodying the 30 principles of my invention; Fig. 3, a vertical section showing a modification of Fig. 1; Fig. 4, a similar section of a modification of Fig. 2; Fig. 5, a section showing a modification of Fig. 1; Fig. 6, a central vertical section through a series of two gas and two air controlling valves, the view showing the valve-operating mechanism in side elevation; and Fig. 7, a top plan view of the said 35 operating mechanism and of the upper parts of the valves and the connection between the gas valves, some of the parts being slightly rearranged.

Referring first to Fig. 1, I show a single 40 gas-controlling structure having the inlet box 1 and the outlet box 2 separated by the annular water-cooled box 3, on the internal flange 4 of which the pendant ring 5 is loosely hung by its external flange 6, which is spaced from the wall of the box 2 into 45 which the ring 5 depends. Directly below the ring 5 and seated at the bottom of the box 2 is the annular trough 7 open upwardly and provided at one side near its bottom with an opening 8 leading to the lip or cup 50 9 having an overflow into the receptacle 10

having the outlet pipe 11 which may lead to a sewer or other place of deposit.

12 is an annular upwardly-open trough containing a tar seal 78 and detachably hung on the periphery of the hollow valve 60 body 13 operated by the hollow stem 14 which extends up through the boxes 1 and 2 and above the former where it has a watertight connection with the chamber 15 in the head 16, the chamber having an outlet pipe 65 17 emptying into the central water-holding compartment 18 on the top casting 19 for the box 1. The compartment 18 overflows into the compartment 20 surrounding the former and having an overflow notch 21 70 which deposits the water into the receptacle 22 having the outlet pipe 23. Water is supplied to the valve-body 13 by the pipe 24 which conducts water to the chamber 25 in the head 16 and above the chamber 15, the 75 water being conducted from the chamber 25 by the pipe 26 which extends through the chamber 15 and the hollow stem 14 and discharges into the valve body 13. Preferably the trough 12 is held from moving off 80 from the valve-body 13 by keys 27. The bottom of the casting 19 has the central opening 28 from which depends the annular water-trough or pocket 29 having its outer wall flush with the bottom of the compartment 18 and its inner wall extending above the top of the said compartment. The stem 14 works vertically in the tubular passage formed by the said inner wall. The head 16 has the pipe 30 screwed into its lower 85 end, and extends down into the pocket 29, the pipe and pocket being of such depths as to maintain a constant water-seal between the box 1 and the atmosphere at all positions of the gas-valve which consists of the 90 valve body 13 and the trough 12.

Water passes from the pipe 24 through the chamber 25, the pipe 26, the valve-body 13, the stem 14, the chamber 15, the pipe 17, the compartments 18 and 20, the notch 21, 100 the receptacle 22 and the pipe 23.

Water in the compartment 18 supplies water to the trough or pocket 29 to seal the pipe 30 so that gas in the box 1 can not escape from the space between the stem 14 and 105 the pocket 29.

31 is the port for admitting fuel gas to the box 1, and 32 is the port by which fuel gas leaves the box 2 on its way to the furnace (not shown), and by which the waste 110

gases from the furnace enter the box 2. 33 is the port by which the waste gases travel from the box 2 on their way to the flue 34 leading to the branch stack flue 35. The 5 box 3 and the trough 7 may be supplied with water from any source.

Referring now to Fig. 2, 36 represents an air-receiving box having on its top the water trough 37 which carries the spider 38 10 having the air-passages or ports 39 and the central hub 40, in which the vertical valve-stem 41 is slidable. 42 is a plate which may be placed over part of the inlet opening 39 to regulate the air supply. The stem 41 supports at its lower end the cup-like valve 43 whose annular flange may be suspended in the annular water trough 44 forming the port 45 for the waste gases which enter the branch stack flue 35 through the flue 46. 15 47 is a second cup-like valve slidable on the stem 41 above the trough 37 and having its flange arranged to enter the trough 37 to form a water seal. The top of the valve 47 carries a number of sheaves 48 and the 20 frame 49 carries above the valve a number of sheaves 50. A number of chains 51 have each one of their ends attached to the stem 41 above the valve 47. Each chain passes over one sheave 50 and under one sheave 25 48 and is attached to the frame 49. 30 48 is the outlet port for the box 36.

For use with regenerative furnaces I prefer to arrange two air valves and two gas valves in line as shown on Figs. 6 and 7. 35 The gas ports 31 of the adjacent gas boxes 1 communicate with the gas-supply passage 53 which is to be connected to gas regenerators (not shown). The lower end of the 40 passage 53 has a valve 54 by the opening of which dust may pass into the receptacle 55 below.

56 is a motor which drives the worm 57 meshing with the worm-pinion 58 on the shaft 59, the latter having the crank 60 connected by the link 61 to the rocking segment 62 turning on the axis 63. Four ropes 64, 65, 66, and 67 work on the periphery of the segment, the left hand ropes 64 and 65 being attached to the right hand end of the 45 periphery, and the right hand ropes being attached to the left hand ends of the periphery. The rope 64 is attached to left hand head 16 and runs on the sheaves 68 and 69, and the rope 66 is attached to the right hand head 16 and runs on the sheaves 70 and 71. The rope 65 is attached to the left hand stem 41 and runs on the sheaves 72 and 73, and the rope 67 is attached to the right hand stem 41 and runs on the sheaves 74 and 75. 55

60 The waste gases from the flues 34 and 46 enter the flues 35 which lead to the main stack-flue 76.

65 The length of the chains 51 is such that either valve 43 or 47 may be in its respec-

tive trough 44 or 37 when the other valve is at its maximum distance away from its seat. The valves 47 must be less than double the weight of the valves 43 and have but half the travel of the latter, owing to the 70 arrangement of the chains as hereinbefore described. The throw of the segment 62 is limited positively in each direction by the dead-center positions of the crank 60 and the link 61, and its throw to the left, as 75 shown on Figs. 6 and 7, (1) lifts the right hand gas valve trough 12 from its sealing trough 7 and moves it up to its sealing connection with the ring 5; (2) lowers the left gas-valve trough 12 from its seal with the ring 5 to its seal with the trough 7; (3) lifts the right hand air valve 43 from its seal with the trough 44 and lowers the corresponding air valve 47 to its seal with the trough 37; and (4) lowers the left hand air 80 valve 43 to its seal with the trough 44 and lifts the corresponding valve 47 from its seal with the trough 37. When the crank 60 and the link are in line with their connections with the shaft 59 and the pivot 77, 85 which connects the link to the segment 62, none of the valves can contact with the bottoms of their respective sealing troughs, thereby preventing damage to the valves and troughs. 90

With the parts positioned as shown on Figs. 6 and 7, fuel gas passes from the passage 53 through the port 31 of the left hand gas valve and thence through its ring 5 and port 32 on its way to the furnace; air passes 100 under the left hand valve 47 to the box 36 and thence through the port 52 on its way to the furnace; and waste gases from the furnace enter the right hand boxes 2 and 36, whence they pass down to the corresponding branch stack flue 35 on their way to the main stack flue 76. 105

Upon the operation of the motor to throw the crank 180 degrees, the valves are all shifted so that they occupy the alternate 110 positions from those shown on Fig. 6, whereupon air and fuel gas enter the right hand boxes 36 and 1 and the waste gases escape to the stack through the left hand boxes 36 and 2. 115

It is to be noted that the sealing troughs 12 have no means for supplying them with water, but that each is filled with tar prior to its initial operation, the filling being done through the door 79. The solid tar in the troughs 12 will soon melt, and even if the trough with the solid tar should engage a ring 5, no harm would result because the ring would be lifted from its seat by its engagement with the tar. Tar is supplied to the troughs 12 by condensation of the same from the fuel gas by reason of the contact of the latter with the water-cooled valve body 13, stems 14 and pockets or wells 29. 120 Any surplus tar flowing over the troughs 12 130

drops into the troughs 7 and escapes therefrom. In Fig. 3, the depending flange of the ring 5^a and the troughs 7^a and 12^a are of such depths that one sealing connection is not broken until the alternate sealing connection is made.

In Fig. 4, the depths of the water-seal troughs 37^a and 44^a, and of the depending flanges of the air valves 43^a and 47^a are such as to prevent a break of the water seals during the transition changes of the valves.

In Fig. 5, I show the tar-sealing trough 12^b having but slight depth but provided with a depending sealing flange 80 for the trough 7^b. The ring 5^b has also a reduced depth.

The boxes 1 and 36 have the respective inspection doors 81 and 82 opposite their respective ports 31 and 52.

20 I claim—

1. In a gas-valve structure, a hollow gas-valve body, means for causing a cooling fluid to pass through it, an upwardly-open sealing trough carried thereby and provision whereby only liquid condensed from the gas contacting with the said body may flow into the trough.

2. In a gas-valve structure, a hollow gas-valve body, means for causing a cooling fluid to pass through it, an upwardly-open sealing trough carried thereby and detachably connected thereto, and provision whereby only liquid condensed from the gas contacting with the said body may flow into the trough.

3. In a gas-valve structure, a hollow gas-valve body, a hollow body-operating stem communicating with the hollow of the body, means for causing a cooling fluid to pass through it, an upwardly-open sealing trough carried by the body and provision whereby only liquid condensed from the gas contacting with the said body and stem may flow into the trough.

4. In a gas-valve structure for regenerative furnaces, a chamber having a fuel-gas inlet port, a waste port, and a furnace-connecting port, a sealing trough surrounding the waste port, a freely upwardly-movable ring between the gas inlet port and the other two ports and concentric with the said trough, a hollow valve-body, a sealing-liquid collecting and containing trough carried by the valve-body and arranged to project in one position into the first trough and

in another position to receive the said ring, a sealing-liquid in the first trough, and means for causing a flow of a cooling liquid to and from the hollow of the valve-body, the said first trough receiving only liquid 60 condensed from the fuel gas by its contact with the valve-body during its passage from the first to the third port.

5. In a reversing-valve structure, plural gas-controlling valves having upper and lower sealing positions, means including liquid-containing sealing troughs for sealing the valves at each of said positions, means for moving the valves simultaneously in opposite direction to their sealing positions, a power-supplying means operating the valves, including a crank so arranged as to cause the said means to be suspended free of contact with their sealing companions when the said crank is at its dead-center 75 positions, in combination with plural air-controlling valves with upper and lower sealing-trough provisions, and connections from the latter valves to the said crank whereby the said latter valves are suspended 80 free of contact with their sealing companions when the said crank is in its dead-center positions.

6. In an air-valve structure for furnaces, two valves movable in opposite directions, a 85 rod to the lower end of which one valve is attached, and on which the other valve is slidable, a system of cords and pulleys connecting the rod and the valve which is slidable thereon, for supporting and operating 90 the valves in unison, and means for controlling the actuation of the valves.

7. In an air-valve structure for furnaces, two valves movable in opposite directions, a rod to the lower end of which one valve is 95 attached, and on which the other valve is slidable, a multiple system of cords and pulleys connecting the rod and the valve which is slidable thereon, for supporting and operating the valves in unison, the number of 100 cords in each system exceeding two, and means for controlling the actuation of the valve.

8. In a valve structure for furnaces, a central valve body, and a detachable sealing 105 ring carried thereby.

Signed at Pittsburgh, Pa., this 8th day of July, 1922.

HAAKON HELLAN.
